DESIGN FOR A COMBINED TABLE AND REMOVABLE TRAY

George A. Huth, Louisville, Ky., assignor to Adler
Manufacturing Co., Incorporated, Louisville,
Ky., a corporation of Kentucky

Application March 8, 1941, Serial No. 99,423

Term of patent 14 years

To all whom it may concern:

Be it known that I, George A. Huth, a citizen
of the United States of America, residing at
Louisville, in the county of Jefferson and State
of Kentucky, have invented a new, original, and
ornamental Design for a Combined Table and
Removable Tray, of which the following is a
specification, reference being had to the accom-
panying drawing, forming a part thereof.

Fig. 1 of the drawing is a perspective view of
a combined table and removable tray embody-
ing my new design.

Fig. 2 is a perspective view of the tray of Fig. 1
apart from the table.

Fig. 3 is a fragmentary perspective and sec-
tional view showing the formation of a part of
the table enabling the same to accommodate a
leg of the tray, this formation being substan-
tially duplicated at each of the other three cor-
ners of the table to accommodate the other three
legs of the tray.

I claim:

The ornamental design for a combined table
and removable tray, substantially as shown and
described.

GEORGE A. HUTH.
